MAXWELL M. UPSON, OF ENGLEWOOD, NEW JERSEY, ASSIGNOR TO CHARLES R. GOW COMPANY, OF BOSTON, MASSACHUSETTS, A CORPORATION OF MASSACHUSETTS.

MAKING CONCRETE FOUNDATION PIERS AND THE LIKE.

Application filed May 11, 1923. Serial No. 638,155.

This invention relates to the construction or formation of concrete columns, piers and the like in the ground, for foundations and other purposes, and its chief object is to provide a simple and effective method by which such piers, of the necessary strength and bearing capacity, can be constructed at low cost in earth which is in part dry and in other parts saturated with or contains water in such amount as to cause excessive inflow or seepage into the excavation. In carrying out the invention in the preferred manner the shaft in which the concrete pier is to be cast is begun by sinking, through each other into the ground, a series of concentric steel shells of successively smaller diameter; the largest being sunk first, then the next largest inside of the first, and so on through the dry or non-waterbearing part of the ground. After each shell is driven, and before the next is sunk, the soil enclosed by the driven shell is removed, so that a hole is produced lined with steel which effectually prevents caving or slipping and therefore permits working close to existing foundations and buildings without injury thereto. As will appear more fully hereinafter, these shells constitute a temporary lining for the upper and naturally dry portion of the hole. When the waterbearing material is reached or approached (as may be known by seepage or by previous sinkings or borings) the sinking of the casing shells ceases, and in the hole a concrete cylinder or caisson is placed, preferably fitting the lowermost shell closely enough to prevent excessive seepage outside of the caisson into the lined upper portion of the hole as the caisson is sunk through the waterbearing strata. The concrete cylinder, as will appear more fully hereinafter, serves also as a permanent lining for the hole at the point where such a lining is necessary or desirable. The cylinder may be cast in the hole, using suitable forms for the purpose, or it may be cast outside and inserted into the hole. In most cases the caisson is of such length that when sunk to rock or hard bearing material its upper end will still be in the lined portion of the hole, say far enough up in the lowermost shell, to continue to exclude excessive seepage or inflow of water during the filling of the hole with concrete.

The caisson having been established in the lined hole, an air lock is placed in the cais-

son and air is pumped into and through the latter, to a pressure sufficient to keep water in undue amount out of the caisson, and the hole is deepened by excavating under the latter. Preferably the caisson is lowered or pressed down through the hole, into the ground, keeping pace with the excavation. When rock or hard bearing material is reached or approached near enough a layer of concrete is deposited thereon, of sufficient thickness to seal the lower end of the caisson against excessive inflow after the air pressure is relieved. When the concrete has set hard enough to serve the purpose indicated the air lock can be removed. The hole is then filled with concrete and as the filling rises in the upper lined portion of the hole the shells forming the lining thereof are withdrawn one after the other for reuse.

The method outlined above is illustrated in various stages in the accompanying drawings, in which—

Fig. 1 is a section showing the lined hole produced by sinking the steel shells, before the caisson is put in place;

Fig. 2 is a section showing the caisson and air lock in position, ready for the deepening of the hole to rock or other hard bearing material;

Fig. 3 is a detail section illustrating a caisson provided with an enlarged or thickened lower end to form a better cutting edge and decrease the friction on the outside of the caisson as the latter descends;

Fig. 4 is a section showing the excavation completed, the caisson sunk to rock, the concrete seal cast in the lower end of the caisson, and the air lock removed;

Fig. 5 is a section showing the hole partially filled with concrete. This figure also illustrates the provision of an enlarged footing below the caisson;

Fig. 6 is a detail section illustrating a method of pressing the caisson into the ground or holding it down against the lifting effort of the air pressure.

Fig. 7 is a section of the lower portion of the forms which may be used when a caisson is to be cast within a hole.

As indicated in the drawings, the steel shells 10, 11, 12, 13, of any suitable size and preferably cylindrical in form, are of successively smaller diameter so that one can descend through the other. The largest

is first driven or otherwise sunk in the ground, followed by the others in order, the soil in the last driven being removed before the next is sunk. Four such shells are shown, but of course the exact number is immaterial and depends upon the length of the individual sections or shells and the depth at which inflow or seepage becomes or would become excessive. When such point is reached (as in Fig. 1, for example) the sinking of the lining shells ceases, and a hollow concrete cylinder or caisson 14 is established in the lined hole, as in Fig. 2. This caisson may be cast in one piece of the necessary length, or its length may be increased as the work progresses by casting or fitting additional sections on top. As indicative of this method I have shown the reinforcing bars or members 15 extending above the top edge of the caisson in Fig. 2. As previously stated, the concrete caisson should fit the lowermost shell, 10, snugly enough to insure against excessive seepage or inflow up around the outside of the caisson and into the shell-lined part of the hole. An air lock, indicated diagrammatically at 16, is now placed in the caisson and adequate air pressure applied therethrough, after which the hole is deepened by excavating inside of the caisson. As the work proceeds, the caisson descends, forming a rigid and substantial lining which prevents caving or collapse of the walls of the hole and permitting the excavation to be carried on rapidly and safely. To facilitate the downward progress of the caisson the lower end thereof may be beveled, as in Fig. 2, for example. Preferably the lower end is provided with an enlargement, as indicated at 17, Figs. 3, 4 and 5, to form a strong and substantial edge, and also to make the hole (as the caisson descends) slightly larger in diameter than the body of the caisson and thereby diminish the friction on the sides of the latter in its downward movement. This enlarged or thickened edge can be provided in any convenient way. For example, on a caisson which is cast in place, it can be produced by suitable shaping of the hole below the lowest shell, 10; or, if the caisson is made outside and inserted in the hole, the enlarged lower edge can be cast on to it in the same manner, or the lower edge of the caisson may be banded with sheet metal, not shown, secured to the concrete by any convenient means.

When rock or other hard bearing material 18, Fig. 4, is reached, the lower end of the caisson is sealed or closed, as by means of a mass of concrete 19 deposited on the rock in sufficient amount to extend well up into the caisson and allowed to set firmly enough to seal the bottom of the hole against undue seepage or inflow. The air

pressure can then be relieved and the air lock removed. I now have a lined hole, extending down to rock or hard bearing material as in Fig. 4, and at least dry enough to permit the rest of the work to be carried out in the open air.

The hole is now filled with concrete. When the filling reaches or approaches the top of the permanent lining (which, it will be understood, is left in place) the lowermost steel shell 10 is pulled out and the filling continued to the next shell, 11, which is then pulled and the filling continued, and so on to the top. In some situations, as for example where excessive lateral pressures are encountered, it may be necessary to let the successive fillings set firmly enough to resist such pressure before pulling the shell next above. In this way it is possible to remove all the shells under conditions which would otherwise make such course dangerous if not impossible.

If desired, the lower end of the concrete column can be provided with an enlarged footing, to afford larger bearing surface, thereby distributing the total load and decreasing the load per unit area. Such a belled or enlarged end is shown in Fig. 5, and may be produced by suitable enlargement of the hole below the caisson, the descent of which is arrested at a suitable point above the rock, 18. The initial body of concrete, for the seal 19, is then deposited in sufficient amount to fill the enlarged excavation and extend up into the caisson.

It is not always necessary to establish the caisson in the shell-lined hole as soon as water-bearing material is reached. In fact it frequently happens that the shells can be driven through a water-bearing stratum and the water cut off thereby, permitting excavation to be continued beyond, in the open air, until material is reached which carries so much water that it cannot be excluded by the shells alone.

In some situations the lifting effort of the air pressure in the caisson may, at depths of more than, say, twenty-five feet or so, be sufficient to overcome the total weight of the caisson and air lock and thus arrest or prevent descent of the caisson. In such cases I prefer to utilize the friction of one or more of the steel lining shells against the earth to press the caisson down into the ground. For this purpose I may provide a suitable number of standards 20 around the outside of the caisson, at the top thereof, and fasten them removably to an appropriate shell or shells, in the present instance the shells 12 and 13, as by a lug-and-slot construction, not shown. Each standard is provided with a vertically adjustable shelf 21, extending inwardly to serve as an abutment for a screw jack 22, by which the necessary downward pressure can be exerted on the caisson.

When the maximum travel of the jack is reached the abutment shelf is lowered on the standard and the operation continued. I have shown only one standard, shelf, and jack, but two or more should be used, spaced around the caisson, to keep the latter straight and moving evenly.

As stated above, the caisson or traveling lining cylinder may be cast outside of the hole, or inside of the same. The latter course is, in some cases at least, preferable, as it keeps the working area above ground free for more economical carrying on of the construction job. For casting the caisson in the hole, I may use sheet steel forms, as in Fig. 7, for example, in which 23 and 24 designate inner and outer forms providing an annular space between them to receive the concrete. The lower form 23 fits into the lining shell 10 and the upper forms are superposed one on the other. The lower form 24 may rest directly on the ground, which is shown enlarged to provide the thickened cutting edge 17 (Fig. 3) of greater diameter than the shell 10. The forms of either or both series may be split longitudinally, as indicated at 25 and 26, to facilitate removal after the concrete has set. If the sheet metal of which the forms are made is not stiff enough to prevent distortion during the casting any convenient means, not shown, may be used outside of the outer series 23 and inside of the inner series 24 to hold them in shape. In most cases it is desirable to cast the entire caisson at one operation, as this method avoids the necessity of interrupting the work of excavation to permit lengthening the caisson by casting additional sections thereon.

It is to be understood that the operations described in the foregoing constitute the preferred practise but that the invention can be carried out in other ways without departure from its spirit as defined by the following claims.

I claim—

1. In a method of forming concrete piers and the like in situ, sinking into the ground, through each other in succession, a series of concentric shells of successively smaller diameter and removing the soil from the shells as the sinking thereof proceeds, to produce a hole having a lining capable of preventing caving and slipping due to lateral pressure; establishing in the shell-lined hole thus produced a downwardly movable permanent lining section of concrete and applying air pressure therethrough to prevent excessive seepage or inflow of water from below; excavating inside the permanent lining section to deepen the hole, and as the deepening proceeds moving the permanent lining section downwardly to prevent caving and undue seepage in later stages, until the desired depth has been reached; sealing the lower

end of the permanent lining section to permit relieving the air pressure without causing excessive seepage or inflow; filling the hole above such seal with concrete, and as the filling rises in the shell-lined portion of the hole, withdrawing the shells in succession.

2. In a method of forming concrete piers and the like in situ, sinking into ground, through each other in succession, a series of concentric shells of successively smaller diameter and removing the soil from the shells as the sinking thereof proceeds; casting in the lined hole thus produced a concrete permanent lining section adapted to move downwardly through the shell of smallest diameter to form a permanent lining for a lower portion of the hole; applying air pressure through the permanent lining section to prevent excessive inflow or seepage from below; deepening the hole below the shells by excavating inside of the caisson, and as the excavation proceeds, moving the permanent lining section downwardly to prevent caving or collapse of the walls of the hole; sealing the lower end of the permanent lining section under air pressure; then filling the permanent lining section and the shell-lined portion of the hole with concrete in the open air, and as the filling rises in the shell-lined portion withdrawing the shells in succession.

3. In a method of forming concrete piers and the like in situ, sinking into the ground, through each other in succession, a series of concentric shells of successively smaller diameter and removing the soil from the shells as the sinking thereof proceeds; casting in the lined hole thus produced a permanent concrete lining caisson adapted to move downwardly through the shell of smallest diameter; applying air pressure through the caisson to prevent excessive inflow or seepage from below; deepening the hole below the shells under said air pressure by excavating inside of the caisson, and as the excavation proceeds, moving the caisson downwardly to prevent caving or collapse of the walls of the hole; and sealing the lower end of the caisson under air pressure to permit relieving the air pressure and filling the hole with concrete in the open air without excessive inflow or seepage from below.

4. In a method of forming concrete piers and the like in situ, sinking into the ground, through each other in succession, a series of removable concentric shells of successively smaller diameter and removing the soil from the shells as the sinking thereof proceeds; casting in the temporarily lined hole thus produced a permanent concrete lining caisson adapted to move downwardly through the shell of smallest diameter and providing the caisson with a cutting edge of greater diameter than said shell to facilitate the descent of the caisson;

applying air pressure through the caisson to prevent excessive inflow or seepage from below; deepening the hole below the shells by excavating inside of the caisson, and as the excavation proceeds, moving the caisson downwardly to prevent caving or collapse of the walls of the hole; and sealing the lower end of the caisson under air pressure to permit the air pressure to be relieved without causing undue inflow or seepage into the caisson from below whereby the concrete to form the pier can be deposited in the open air.

5. In a method of forming concrete piers and the like in situ, producing in the ground a hole having a lining composed of removable concentric shells of successively smaller diameters, establishing in such temporarily lined hole a permanent lining caisson adapted to move downwardly through the shell of smallest diameter, deepening the hole below the shells by excavating inside of the caisson while preventing excessive inflow or seepage into the latter from below and as the deepening proceeds moving the caisson downwardly to serve as a lining for the lower portion of the hole, and sealing the lower end of the caisson, to provide a substantially dry hole for casting the concrete pier, lined in part with the concentric shells and in part with the caisson.

6. In a method of forming concrete piers and the like in situ, producing in the ground a hole having a lining composed of removable concentric shells of successively smaller diameters, establishing in such temporarily lined hole a permanent lining caisson adapted to move downwardly through the shell of smallest diameter, deepening the hole below the shells by excavating inside of the caisson while preventing excessive inflow or seepage into the latter from below, and as the deepening proceeds moving the caisson downwardly to serve as a lining for the lower portion of the hole.

7. In a method of forming concrete piers and the like in situ, sinking into the ground, through each other in succession, a series of removable concentric shells and removing the soil from the shells as the sinking thereof proceeds to produce a hole having a temporary lining; establishing in the hole a permanent lining section in the form of a concrete caisson movable downwardly through the lowermost of the removable shells; deepening the hole by excavating below the lining caisson, and causing the latter to descend to form a permanent lining for the hole below the shells; sealing the bottom of the permanent lining section to prevent excessive seepage and inflow of water; and thereafter filling the hole with concrete and withdrawing the removable shells.

8. In a method of forming concrete piers and the like in situ, sinking into the ground,

through each other in succession, a series of removable concentric shells and removing the soil from the shells as the sinking thereof proceeds to produce a hole having a temporary lining; establishing in the hole a permanent lining section in the form of a concrete caisson movable downwardly through the lowermost of the removable shells; deepening the hole by excavating below the lining caisson, and causing the latter to descend to form a permanent lining for the hole below the shells; enlarging the hole laterally below the caisson; filling the enlarged portion of the hole and the bottom of the permanent lining section with concrete to seal the latter and provide an enlarged footing for the pier; and thereafter filling the hole with concrete and withdrawing the removable shells.

9. The method of forming concrete piers and the like in situ and under substantially normal atmospheric pressure conditions comprising, sinking into the ground, through each other and in succession, a series of concentric shells of successively smaller diameter and removing the soil within the limits of the shells as the sinking thereof proceeds to produce a hole whose depth extends to limits where water seepage renders excavating to a lower depth impracticable without the use of compressed air; establishing in the shell-lined hole thus produced a lining section of concrete whose outer dimension is less than the inner dimension of the last shell to be positioned; applying air pressure within said section; excavating inside the concrete lining section to deepen the hole, and, as the deepening proceeds, moving the concrete lining section downwardly to maintain the hole open; sealing the lower end of the concrete lining section to permit relieving the air pressure without allowing excessive seepage or inflow; removing the air pressure from within the closed confine of the concrete lining section; and filling the hole under substantially normal atmospheric pressure conditions.

10. The method of forming concrete piers and the like in situ and under substantially normal atmospheric pressure conditions comprising, sinking into the ground, through each other and in succession, a series of concentric shells of successively smaller diameter and removing the soil within the limits of the shells as the sinking thereof proceeds, to produce a hole whose depth extends to limits where water seepage renders excavating to a lower depth impracticable without the use of compressed air; establishing in the shell-lined hole thus produced a lining section of concrete adapted to fit within the area of the lower-most shell and being of a length sufficient to extend from the lower-most shell to hard bearing material; applying air pressure within said section;

excavating within the concrete lining to deepen the hole and cause the concrete lining to move downwardly; sealing the end of the concrete lining section when the hole has been excavated to the desired extent; relieving the closed confines of the concrete lining section from air pressure; and casting a pier under substantially normal atmospheric pressure by filling the entire extent of the opening produced by excavating.

11. The method of forming concrete piers and the like in situ and under substantially normal atmospheric pressure conditions comprising, producing in the ground a hole having a lining comprising successive shells; deepening this hole by the addition of shells and additional excavation to a depth where

deeper excavating is impracticable without the use of compressed air; establishing a single caisson within said hole adapted to be lowered to a depth desired and having sufficient length to extend from the lowermost casing to the depth desired; establishing within said caisson air pressure; lowering the caisson by excavating to the depth desired; sealing the lower end of said caisson to maintain the hole dry when the air pressure is relieved; relieving the air pressure from within the caisson; and filling the hole under normal pressure conditions.

In testimony whereof I hereto affix my signature.

MAXWELL M. UPSON.
